MINING MACHINE

Frank A. Lindgren, Western Springs, Ill., assignor to Goodman Manufacturing Company, Chicago, Ill., a Corporation of Illinois

Application March 27, 1930. Serial No. 439,305

4 Claims. (Cl. 262—28)

This invention relates to improvements in mining machines and has for its principal object to provide an improved mining machine of the shearing type adapted to make a vertical or shearing cut in a mine wall extending from the mine bottom to the mine roof perpendicular to the mine wall or at various angles with respect thereto.

A prior application Serial Number 344,677, filed March 6, 1929, shows a shearing machine adapted to make a vertical cut in a mine wall at various angles with respect thereto. While the machine of my present invention is somewhat similar to that shown in my prior invention, the machine of my present invention discloses a new and improved means for raising the entire machine above the mine rails so the machine may be turned at various angles with respect to the mine face for cutting a vertical kerf therein.

My invention may be more clearly understood with reference to the accompanying drawings wherein:

Figure 1 is a top plan view of the device embodying my invention with parts broken away and in section;

Figure 2 is a side elevation of the device shown in Figure 1 with parts broken away and in section;

Figure 3 is a side elevation of the device shown in Figure 2 with the device embodying my invention positioned in a different position than is shown in Figure 2;

Figure 4 is an enlarged partial fragmentary side elevation of the machine with parts broken away and in section; and

Figure 5 is an enlarged sectional view taken on line 5—5 of Figure 4.

Like numerals refer to like parts throughout the several figures.

Referring now in particular to the drawings, I have provided a cutting element generally indicated at 10 reciprocably movable in a guide frame 11 pivoted at its rearward end to a base frame 12 on a transverse shaft 13, which base frame is supported on axles 15, 15 and wheels 16, 16.

The cutting element 10 is similar to that of the ordinary breast machine but is turned on its side to make a vertical instead of a horizontal cut and is fully disclosed in a prior application Serial Number 158,290, filed December 31, 1926, so will only be described in so far as is necessary to fully disclose my present invention. The cutting element 10 comprises a cutter bar 17 reciprocably movable in the guide frame 11 and having an endless cutter chain 18 movable there-

about. The cutter chain 18 is driven from a motor 19 herein preferably shown as an electric motor, through a suitable gear train of an ordinary type which includes a motor pinion 21, external gear 22, bevel pinion 23, bevel gear 24, and sprocket 26.

Reciprocable movement of the cutting element 10 is obtained by sprockets 27 which mesh with racks 28 on the top and bottom sides of stationary guide frame 11. Said sprockets are driven by the motor 19 at one speed in one direction and at a different speed in the opposite direction by a suitable gear train in a usual manner which is fully described in my prior application, Serial Number 158,290, hereinbefore mentioned but is not herein described in detail since it is not part of my invention.

Pivotal movement of the cutting element 10 about the axis of the shaft 13 is effected by a vertically adjustable support indicated at 29 on the forward portion of the base frame 12. Said vertically adjustable support includes a pair of parallel spaced racks 30, one of said racks being on each side of the cutter bar 17 and each of said racks being pivotally mounted on the base frame 12. The racks 30 are guided in a frame member 31 extending outwardly from the guide frame 11 and fixed thereto. Pinions 32, 32 are fixed on a transverse shaft 33 journaled in the frame member 31 on each side of the cutter bar 17 and mesh with the racks 30 so rotation of said pinions will move the frame member 31 along the racks 30 to move the cutting element 10 about the axis of the shaft 13 which effects vertical movement of the cutter bar 17 to make a vertical cut in a mine wall. The transverse shaft 33 is driven from the motor 19 by means of a telescoping drive shaft 34 and a suitable system of reduction gears enclosed in a housing 35, which gear train is of an ordinary construction well known to the art and is generally indicated by dotted lines at 36 in Figures 2 and 3.

Referring now in detail to several of the novel features of my invention which include a novel means for raising the mining machine above the mine rails so said mining machine may be turned at various angles with respect to the rails, a raising means which herein comprises a jack 37 is provided on the longitudinal center line of the machine and spaced midway between the axles 15—15.

The jack 37 includes a housing 38 having ears 39, 39 projecting outwardly therefrom, which ears are attached to the underside of parallel

spaced angles 40, 40 extending transversely of the base frame 12. The housing 38 has a cover 41 detachably mounted thereon. A cylindrical wall 42 is formed within the housing 38 and 5 affords a vertical sliding support for a cylindrical portion 43 of a jack foot 44. The cylindrical portion 43 of the jack foot 44 is feathered within the cylindrical wall 42 by means of a feather key 45 and has a threaded sleeve 46 10 therein. The threaded sleeve 46 is fixed to the cylindrical portion 43 of the jack foot 44 by a set screw 47. A shaft 48 is threaded within the sleeve 46. The threaded shaft 48 depends from and is keyed on a bevel gear 49, which bevel gear has bearing support on the top portion of 15 the cylindrical wall 42 and the inside of the cover 41 by means of a thrust ball bearing 50 fixed on a hub 51 of the bevel gear 49.

A bevel pinion 52 is fixed on a shaft 53 and 20 meshes with the bevel gear 49. The shaft 53 is journaled within a housing 54 fixed to the housing 38 and extending outwardly therefrom. This housing also encloses a worm gear 55 keyed on the outer end of the shaft 53 and a worm 25 56 cut integral with a shaft 57, which shaft is journaled within said housing. The rearward end of the shaft 57 is squared and fits in a connecting link 59. A squared end of a shaft 60 30 fits in the opposite end of said connecting link and extends rearwardly therefrom. The shaft 60 is supported in a bearing member 61 near its rearward end and has a squared socket 62 at its rearward end. Suitable friction drive means herein comprising a disk type of friction clutch 35 63 of a usual construction are interposed between the socket 62 of the shaft 60 and a drive shaft 65. The drive shaft 65 is journaled in a bearing 64 integral with a motor support bracket 66. The shaft 65 has a head 67 thereon abutting the rearward end of the bearing 64. A 40 spur gear 68 is keyed to the forward portion of the shaft 65 and abuts the rearward portion of the friction clutch 63. A motor 69 is supported on the motor support bracket 66 for driving the spur gear 68 by means of a spur pinion 70. Thus 45 the motor 69 drives the bevel gear 49 and threaded shaft 48 through the spur gear 68, friction clutch 63, worm 56, worm gear 55 and bevel pinion 52 which drives the threaded shaft 48 and causes vertical movement of the threaded sleeve 46 and jack foot 44.

The jack foot 44 comprises a circular base member 73 supported on a plate 74. Balls 75 are 50 interposed between the under portion of the base member 73 and top portion of the plate 74 and ride in races 76 on the under portion of the base member 73 so the base member 73 and the entire mining machine may be rotatably moved with respect to the plate 74 when said plate is engaged with the mine bottom and the mining machine is supported on said plate. Means are provided to guide the base member 73 of the jack foot 44 on the plate 74 which comprises a ring 77 fixed to the top portion of the plate 74 by a suitable means, which means is herein shown as machine screws 78. The ring 77 has a flange 79 extending inwardly therefrom, which flange abuts a shoulder 80 on the outer periphery of the base member 73.

Figure 2 shows the mining machine on the mine rails and Figure 3 shows the jack foot 44 engaging the mine bottom and shows the mining machine positioned at right angles to the mine rails. 70 When the mining machine is positioned at right angles with respect to the mine rails, angles 81,

81 are laid crossways of the track and are adapted to be engaged by the track wheels 16 to support the mining machine when the plate 74 of the jack foot 44 is disengaged from the mine bottom. This forms a support for the mining machine when it is desired to cut a vertical kerf at right angles to the mine track proper or at various angles with respect thereto. 30

When desired the jack 37 may be used to position the mining machine so it may be moved 35 from one track to another without the use of switches; as, for instance, when the mining machine is supported on the angles 81, 81 crossways of the main track said mining machine may be moved from said angles onto rails in alignment 90 with said angles. It may be noted that the angles 81 may be placed in various positions on the rails so the mining machine may be moved onto tracks at various angular positions with respect to the main track. This is especially advantageous when it is desired to cut in remote parts of the mine not fully developed where it is uneconomical to provide switches into each cutting place and where conveyors or loading machinery of various types are in use and it is not desired to go to the 100 expense of providing switches into the mine rooms.

It may thus be seen that I have provided a mining machine adapted to make shearing cuts in a mine wall, which mining machine is provided with a raising and turning means for raising the mining machine above the mine rails and allowing said mining machine to be turned at various angles with respect to the rails to cut in various positions with respect to the mine rails. 105 It may also be seen that the raising and turning device may also serve to eliminate switches when used in conjunction with the angles 81 as has been fully described.

While I have herein shown and described one 115 form of my invention, it will be understood that the construction and arrangement of the various parts may be altered without departing from the spirit and scope thereof. Furthermore, I do not wish to be construed as limiting myself to the 120 specific form illustrated, excepting as it may be specifically limited in the appended claims.

I claim as my invention:

1. In a mining machine, a track-mounted base frame, a cutting element thereon including a reciprocably movable vertically disposed chain-carrying cutter bar, a motor on said base frame on one side of said cutter bar for driving the cutter chain, for reciprocating the cutter bar, and for driving the truck wheels to propel the apparatus, a jack supported on the base frame including a jack foot engageable with the mine bottom, and a separate motor mounted on the base frame on the opposite side of said cutter bar from said first-mentioned motor and having driving engagement with said jack. 125

2. In a mining machine, a track-mounted base frame, a cutting element thereon including a reciprocably movable vertically disposed chain-carrying cutter bar, a motor on said base frame on one side of said cutter bar for driving the cutter chain, for reciprocating the cutter bar, and for driving the truck wheels to propel the apparatus, a screw jack supported by said base frame and depending therefrom including a jack foot engageable with the mine bottom, and a separate motor mounted on said base frame on the opposite side of said cutter bar and having driving engagement with said jack. 140

3. In a track-mounted mining machine, a base 150

frame, a cutting element thereon including a reciprocably movable vertically disposed chain-carrying cutter bar, a motor on said base frame for driving the cutter chain, for reciprocating the cutter bar, and for driving the truck wheels for propelling the apparatus, and means for positioning said cutter bar for cutting a vertical kerf at various angles with respect to the mine wall comprising means for raising said base frame and cutting element above the track and supporting said base frame for rotation about a vertical axis, said means comprising a jack carried by said base frame intermediate said track wheels including a jack foot engageable with the mine bottom, and a separate motor on said base frame having driving engagement with said jack.

4. In a track-mounted mining machine, a base

frame, a cutting element thereon including a reciprocably movable vertically disposed chain-carrying cutter bar, a motor on said base frame for driving the cutter chain, for reciprocating the cutter bar, and for driving the truck wheels for propelling the apparatus, and means for positioning said cutter bar for cutting a plurality of vertical kerfs at various angles with respect to the mine wall comprising means for raising said base frame and cutting element above the track and supporting said base frame for rotation about a vertical axis, said means comprising a screw jack supported by said base frame including a jack foot engageable with the mine bottom, and a separate motor mounted on said base frame having driving engagement with said jack.
